UNITED STATES PATENT OFFICE.

HECTOR MACLEOD, OF GUELPH, ONTARIO, CANADA, ASSIGNOR TO KAWNEER MANUFACTURING COMPANY, OF NILES, MICHIGAN, A CORPORATION OF MICHIGAN.

TRAILING EDGE FOR AIRPLANES.

1,355,611.

Specification of Letters Patent.

Patented Oct. 12, 1920.

Application filed September 22, 1917. Serial No. 192,648.

To all whom it may concern:

Be it known that I, HECTOR MACLEOD, a subject of the King of Great Britain, residing at Guelph, in the county of Wellington and Province of Ontario, Canada, have invented certain new and useful Improvements in Trailing Edges for Airplanes, of which the following is a specification.

This invention relates to aircrafts and more particularly to edgings for the trailing edge of the wings, and also to edgings for ailerons, rudders, elevating planes, and the like.

In the construction of airplanes as heretofore conducted, the securing of the cross ribs of the ailerons, wings, rudders, stabilizers, and the like, to the edging member has been effected in an inefficient and impractical manner, as by butting the end of the rib against the tube edging member and securing the same in place by means of straps passing around the tube edging members. This has proven very unsatisfactory for many reasons, among which are the excessive cost, the insecurity of the connection, the additional weight necessary in the edging member, the consumption of too much time in building, and the general lack of simplicity, adaptability, neatness, efficiency, compactness, and economy. These difficulties have been entirely overcome by this invention.

Among the objects of my invention, therefore, is to provide a new and useful edging for aircraft wings, ailerons, rudders, and the like; further to provide a novel form of connection between the end of the ribs and the edging member; further to so edge the wings, ailerons, rudders, and the like, of aircrafts that the maximum of lightness, efficiency, neatness, strength, simplicity, compactness, and economy is effected; and such further objects and advantages as will hereafter become more apparent.

My invention further resides in such combination, construction, and arrangement of parts as disclosed in the accompanying drawing, and while I have illustrated therein in a preferred embodiment, I desire the same to be understood as illustrative only and not as limiting the scope of my invention.

In the drawings:

Figure 1 is a plan view of an aileron embodying my invention.

Fig. 2 is a perspective view of a portion of my new edging member and showing the manner of connecting the rib thereto.

Fig. 3 is a section through the line 3—3 of Fig. 2, and showing the filler strips 8 and 60 added.

Referring to the drawings, Fig. 1 shows an aileron consisting of a framework indicated generally as 1, and made up of a rear edging member 2, cross ribs 3, and covering material 4. The edging member 2 which houses the ends of the ribs is formed U-shape in cross section out of a suitable gage and width of metal, as clearly shown in Fig. 3, the free edges of which are slightly inclined inwardly toward each other forming lips 5 and 6. This inclined feature of the lips 5 and 6 provides additional strength and prevents the covering from wearing by friction at these places. The cross ribs 3, which may be of light, strong wood or metal, or other suitable material, are tapered so as to fit into the trailing edging member, as shown at 7 between the lips 5 and 6.

By having the rib ends fit between the lips 5 and 6 and within the edging member 2 these parts will be effectively held together not only by the tightness of the fit but also by the fastenings (any suitable kind being used) and covering material which is drawn tightly around the edging member and secured in place. When metal ribs are used they may be welded, brazed, or otherwise suitably secured in place within the edging member.

It is to be noted that the particular shape of the edging member as shown in the drawings is such as to give not only the maximum of strength for the metal used, but also the maximum of lightness, and at the same time reduce the vacuum at the rear to the minimum. While in the drawings I have shown this edging member as applied to the rear edge of an aileron, (which position it would also occupy in wing construction,) it is to be understood that when the same is used as an edging for rudders, stabilizers, or the like, it may be extended entirely therearound, or over the ends, instead of being confined only to the rear edge, if such be desired. Also at times it might be found desirable to extend the same partially around the ends of wings and ailerons. The shape of the edging member 2 is such as to permit the covering

material to be drawn around and over the same without damage to such covering. Also the use of the filling strips 8 and 9 brings the sides of the edging member 2 flush as shown in Fig. 3, which further greatly facilitates the application of the covering material to its place.

Having now described my invention, I claim:

- 10 1. In aircraft construction, ribs, facing strips on opposite edges of said ribs terminating short of the ends of said ribs, an edging strip, generally U-shaped in cross section with the ends of the U inclined slightly toward each other, said edging strip embracing the ends of the ribs and abutting the ends of the facing strips.
- 15 2. In aircraft construction, ribs, facing strips on opposite edges of said ribs terminating short of the ends of said ribs, an edging strip, generally U-shaped in cross section with the ends of the U inclined

slightly toward each other, said edging strip embracing the ends of the ribs and abutting the ends of the facing strips, the covering material of the planes or ailerons being drawn tightly over the edging strips to hold the same in place. 25

3. In aircraft construction, a hollow edging member having a slot therein, the free edges of said member along said slot being inclined toward each other, a rib having an end adapted to fit into the hollow of said member, and filling strips on said rib and substantially abutting said inclined portions whereby to hold the covering material without undue chafing. 30 35

In witness whereof I hereunto subscribe my name to this specification in the presence of a witness.

HECTOR MACLEOD.
